OXWELD ACETYLENE COMPANY, A CORPORATION OF WEST VIRGINIA.

ACETYLENE-GAS GENERATOR.

1,148,496.

Specification of Letters Patent.

Patented Aug. 3, 1915.

Application filed December 19, 1911. Serial No. 666,800.

To all whom it may concern:

Be it known that I, ROBERT D. BRADEN, a citizen of the United States, residing at Chicago, in the county of Cook and State 5 of Illinois, have invented certain new and useful Improvements in Acetylene - Gas Generators, of which the following is a specification.

This invention relates to acetylene generators of the carbid feed type, and has reference more particularly to an improved underground generator designed for installations where it may not be practicable or desirable to install the generator inside the 15 building, such as houses having no basements, churches, and other buildings which are not continuously heated during freezing weather.

Among the leading objects of the invention are, to provide a generator of this type, which, even though when installed outside of insured property shall, nevertheless, be constructed in accordance with established standards of safety and efficiency and comply with the rules and requirements of the 20 National Board of Fire Underwriters governing acetylene lighting apparatus; to provide a generator of this type wherein the carbid holder and its feed mechanism are 25 combined in a single removable structure and may be held in place without bolts or other fastening means, and may be readily removed without the use of wrenches or other tools; to provide means for facilitating 30 the removal and replacement of the storage bell and carbid holder and its feed mechanism; to provide, in a generator of this type, improved means for removing the residuum, and for re-filling the generation 35 chamber with water; to provide a sensitive and reliable mechanism for effecting the feed of carbid through the rise and fall of the storage bell; to provide an improved mechanism for indicating the amount of 40 carbid in the carbid holder and showing when the same must be refilled; to provide means for indicating to the operator when the generation chamber has been filled with 45 water to the required height; and, generally, to provide a simple, compact, easily handled and highly efficient automatic gas generating apparatus of the type specified. 50 These and other minor objects and advantages are attained by the mechanism illustrated in the accompanying drawings con-

stituting one approved mechanical embodiment of the invention, and in which,—

Figure 1 is a view of my improved generator partly in side elevation and partly in axial vertical section, broken out between its ends; and showing the same located within a suitable pit or cistern. Fig. 2 is an enlarged cross-section through the generator on the line 2—2 of Fig. 1. Fig. 3 is a top plan view of the carbid hopper. Fig. 4 is an enlarged detail in vertical section showing the means for supporting and protecting the upper end of the stem of the feed valve. Fig. 5 is a perspective detail, broken off and partly in vertical section, illustrating the joint between the pivoted carbid indicator arm and the actuating mechanism connecting the same to the pointer of the indicator scale. Fig. 6 is a detail fragmentary view, partly in elevation and partly in vertical section illustrating a separable joint in the actuating rod of the agitator permitting the removal of the handle of the latter when in use. Fig. 7 is a cross-sectional detail on the line 7—7 of Fig. 6. Fig. 8 is a detail fragmentary elevation of the indicator scale and pointer.

Referring to the drawing, 4 indicates a suitable pit or cistern within which the generator is installed, the pit being preferably of somewhat greater diameter than the outer casing of the generator, and the space between the latter and the walls of the pit being filled in with cement or grouting indicated at 5.

6 designates a cylindrical outer casing or tank, preferably of sheet metal, that is adapted to be set within the pit, and is of such a length that the water in the generation chamber formed within the lower portion of the tank, and the water seal of the storage bell thereabove, will both be safely below the frost line. Within and preferably coaxial with the tank 6 is a smaller and shorter stationary cylinder 7 open at both 95 ends and having at its lower end an annular flange 8 that is secured to the inner surface of the tank 6, as by rivets 8a (Fig. 2), thereby forming an annular water seal chamber 9 between the inner cylinder 7 and the tank 6. 100

On the upper edge of the cylinder 7 rests the carbid receptacle designated as an entirety by 10. This latter, in the preferred form herein shown, comprises an upper cylindrical body portion 11, a hopper bottom 110

12, and a cylindrical lower portion or apron 11^a surrounding the hopper bottom and conveniently forming a downward extension of the cylindrical body portion 11 which 5 telescopes loosely within the stationary cylinder 7, and with sufficient freedom to permit the ready passage of gas from the underlying generation chamber between said telescoping parts, for a purpose hereinafter 10 disclosed. The carbid receptacle is conveniently supported on the upper edge of the stationary cylinder 7 by means of a series of lateral projections conveniently taking the form of vertical ribs 13 formed on the 15 cylindrical body portion of the carbid receptacle, the lower squared ends of these ribs 13 resting directly upon the upper edge of the cylinder 7. The body of the receptacle is provided with a top wall or cover 14, 20 equipped with the usual filling plug 15, and further provided with a handle 16 for convenience in removing the carbid receptacle from the tank of the generator.

Surrounding and covering the carbid receptacle and at its lower portion dipping within the water seal chamber 9 is a storage bell 17 provided on its top wall with a handle 18 for convenience in removing and replacing the same. This storage bell is 25 guided in its rising and falling movements by the outer edges of the ribs 13 of the carbid receptacle, with which it has a loose sliding fit. The lower end of the hopper bottom 12 has a feed opening guarded by a conical feed valve 19 of the vertical moving type, 30 said valve coöperating with a hood or shield 20 located a slight distance above the valve-controlled feed opening of the hopper and supported from the walls of the latter by 35 short legs 21 (Fig. 2). In the upper end or apex of the shield 20 is secured a short sleeve 22 (Fig. 4) which forms a guide and stop for the stem 23 of the valve 19, its upper end coöperating with a nut 24 on the 40 upper end of the valve stem 23 to adjust and limit the downward movement of the valve. The guide sleeve 22 and the upper end of the valve stem are protected from 45 the carbid by a thimble 25 that screws down over the upper end of the guide-sleeve 22. The lower end of the valve 19 rests upon one arm 26 of a horizontal lever that is pivoted at 27 to a depending bracket 28 on the carbid hopper, and the opposite arm 29 50 of said lever has pivoted thereto a rod 30 that extends upwardly through a long guide sleeve 31 carried by and partly within the hopper, and at its upper end is adapted, on the descent of the storage bell 17, to be 55 struck by the top wall or cover of the latter so as to raise the valve 19 and permit a flow of carbid thereby into the underlying generation chamber, this latter being indicated by 32. It will be noted that the lower end 60 of the guide-tube 31 extends down substan-

tially to the lever arm 29 when the feed valve 19 is in its lowermost or closing position, and thus, in combination with the said lever safeguards the valve against falling out of place in the possible event that the 70 nut 24 should work loose from the valve-stem, or the latter become broken, or the upper support of the valve be otherwise interrupted.

Suitably secured to and within the main 75 casing or tank 6, as by a bracket 33, is a gas-delivery pipe 34 that extends down through the sealing chamber 9 and through the bottom wall 8 of the latter, so as to communicate freely at its lower end with the generation chamber 32 above the level of the water in the latter. At any suitable point in its 80 height the pipe 34 is connected, by the T-coupling 35, with an underground service pipe 36; and the upper end of the delivery-pipe 34 is provided with a cock 37 which 85 may be opened to permit the ingress and egress of air when the generation chamber is being emptied and filled while the carbid hopper and storage bell are in place. 90

On one side and externally of the tank 6, near the top, is formed a small pocket 38 having a hinged lid 39 and constituting a housing for a scale 40 (Fig. 8) applied to or formed on the wall of the tank, over 95 which scale moves an indicator finger 41 that shows the condition, as to quantity, of the carbid within the receptacle 10. The mechanism through which the indicator finger 41 is actuated comprises, in the preferred form herein shown, an indicator arm or paddle 42 within the carbid receptacle, the broad free end of which normally lies on top of the body of carbid therein. The other end of the arm 42, as shown in the detail view, Fig. 5, has a right-angle extension 43 journaled in one wall of a box 44 that is supported on a guide tube 45 within and secured to the hopper bottom of the carbid receptacle, the arm 42, beyond the angular extension 43, having a further right-angle extension taking the form of a loop 46 which engages a laterally projecting pin 47 on a rod 48. This latter passes through the box 44 and tubular guide 45, its upper portion passing through and extending above the cover 14 of the carbid receptacle, as shown at 49, and its lower portion extending through and below the hopper bottom of the carbid receptacle within the depending apron 11^a and terminating in a small disk or button 50. 110

In a tubular guide 51 secured to and inwardly of the stationary inner cylinder 7 by brackets 62, is slidably mounted a rod 53, the upper end of which engages and forms a contact joint with the underside of the disk 50, while its lower end is connected to the short arm 54 of a lever pivoted at 55 to a depending bracket 56 on the stationary 120 125 130

cylinder 7, the long arm 57 of said lever being connected to the lower end of a long rod 58 guided in a tube 59 that extends through and some distance above and below 5 the sealing chamber. The upper end of rod 58 is bent outwardly to pass through a slot 60 in the wall of the tank, and is again bent to form the indicator finger 41 above referred to as coöperating with the scale 40.

10 From the foregoing it will be apparent that, as the carbid in the receptacle 10 is used and its level lowered, the indicator arm or paddle 42 will gradually drop, and, through the described connections, slightly 15 raise the disk 50. This will permit the long rod 58 carrying the indicator finger and the long arm 57 of the lever to drop by gravity to the extent permitted by the upward movement of the disk 50, which, of course, is constantly 20 engaged by the upper end of the rod 53. The lowest marking on the scale 40 corresponds with the empty condition of the carbid receptacle, and the highest marking on the scale corresponds with the fully 25 charged condition of the carbid receptacle, so that the operator or owner of the apparatus by merely raising the lid 39 and noting the position of the pointer on the scale, can readily ascertain the condition, as to quantity, 30 of the carbid in the receptacle at any time.

Pivoted at 61 on the cover 14 of the carbid receptacle is an interference device in the form of a lever, one arm 62 of which 35 has an upwardly bent end portion 63 normally overlying the filling plug 15, while the other arm 64 has an upwardly bent end portion 65 that normally lies adjacent to but not interfering with the upper end 49 of the rod 48. When the carbid receptacle is to be refilled, the rod 48, 49 is first depressed, and the lever is then swung as indicated by the arrow in Fig. 3 to free the filling plug 15, which carries the end 65 of 40 the rod 48. The lever over the depressed end 49 of the rod, thus holding the indicator arm 42, which has been fully raised by the depression of the rod 48, 49 in such raised position during the refilling of the receptacle. When 45 the receptacle has been charged and the filling plug replaced, the lever is swung back to the position shown in Fig. 3, which releases the rod 48, 49, and restores the free action of the indicator mechanism. It will 50 thus be seen that the utility of the interference device consists in insuring the restoration of the indicator arm or paddle to fully raised position, and also, upon the replacement of the carbid receptacle within the 55 machine, in the restoration of the pointer of the indicator mechanism to fully raised position, whenever the carbid receptacle is recharged.

The outer casing or tank 6 of the machine 60 is provided with a sloping or inclined bottom wall 66, and with a solid or imperforate cover 67 that, when in place, fully protects the internal parts from the ingress of dirt or foreign matter, and from the weather. Within the generation chamber 32 is a tube 70 68 which extends from a point slightly above the lowest point of the bottom wall 66 through the bottom wall 8 of the annular sealing chamber, the upper end of said tube establishing the normal water level in the 75 sealing chamber; said tube also serving as a convenient means for filling the generation chamber with water by overflow from the sealing chamber without the necessity of removing the storage bell and carbid receptacle, although, of course, when the latter parts have been withdrawn for renewing the supply of carbid, the generation chamber may be directly filled by water poured through the cylinder 7. To effect the drainage of the generation chamber, when necessary, I employ a removable pump 69, the tube 69^a of which is secured just inside the wall of the tank 6, as by brackets 70, and extends down, preferably through the tube 80 68, to a point just above the lowest point of the bottom wall 66 of the generation chamber. The pump tube 69^a is threaded at its upper end slightly below the cover 67 to permit the ready attachment thereto, when 85 the cover 67 is removed, of the pump 69. To facilitate the withdrawal of the residuum, I preferably employ an agitator in the form of an arm or sweep 71 that overlies the bottom wall of the generation chamber and 90 is secured to the lower end of an agitator rod 72 extending down alongside the pump tube, said rod being guided in a tube 73 that also preferably extends through the overflow tube 68, as clearly shown in Fig. 2. 100 The agitator rod is preferably, and as here shown, made in two separable sections,—a main section 72 that terminates at its upper end slightly below the cover 67 and is formed with a square socket 74 (see Figs. 105 6 and 7), and a shorter section 72^a having a reduced and squared lower end portion 75 forming a sliding fit with the socket 74, the short section 72^a terminating in a handle 76. From this it will be apparent that the pump 110 69 and the upper section 72^a and handle 76 of the agitator rod are disconnected, and the cover or lid 67 is in place during the normal operation of the machine; but when recharging is necessary, the lid 67 is removed, the pump and rod handle readily applied, whereupon, after operating the agitator for a brief time to stir up and bring to substantially uniform condition 115 the residuum in the generation chamber, said residuum may be pumped out by the pump 69, after which the pump and agitator handle are again disconnected to permit the subsequent application of the lid 67. 120 In this connection it may also be noted that 125 130

there is a distinct advantage in passing the pump tube and the agitator rod and its tubular guide down into the generation chamber through the overflow tube 68, in that such an arrangement dispenses with the necessity of additional soldered joints for the said parts in the bottom wall 8 of the sealing chamber; and this arrangement, further, facilitates the withdrawal of the pump tube, agitator rod, or the tubular guide of the latter, when necessary, since not involving the breaking of a permanent joint or seal between the said parts and the bottom wall of the sealing chamber. The pump tube and agitator rod and its guide may, however, be otherwise disposed, without going outside the invention in its broader aspects.

To insure the correct registration of the carbid receptacle with the stationary cylinder 7 which supports the same so that the disk or button 50 on the lower end of the indicator rod 48 will register and form a contact joint with the upper end of the rod 53 I provide on the outer cylindrical surface 11 of the carbid receptacle a longitudinal rib 77 (see Fig. 2) adapted to have sliding engagement with the slot 78 formed in the cylinder 7.

To facilitate the installation of the apparatus which, in the larger sizes is quite heavy, and more especially the lowering of the same into the pit or cistern, I secure to the upper end of the tank 6 a pair of staples 79 located diametrically opposite each other, and forming a convenient hitch for the ropes or cables of a block and tackle slung from a gin or tripod over the pit.

To facilitate the removal and replacement of the storage bell and carbid receptacle, I preferably provide the tank 6 with a detachable, bail-shaped frame 80, the lower ends of which are adapted to fit within socket-pieces 81 strongly secured to and on opposite sides of the tank 6 at or near its upper end as by clips 82. With the cover 67 removed, the bail 80 is readily mounted in the sockets 81 and constitutes an overhead support for any suitable hoisting and lowering devices adapted to engage the handle 18 of the storage bell and the handle 16 of the carbid receptacle. In the normal working condition of the machine, the frame 80, like the pump and agitator handle, is disconnected and removed.

Across the upper end of the generation chamber 32 extends a strip or bar 83 which is located coincident with the proper level of the water in the generation chamber. The position in which this indicator bar is set is determined by the relative capacities of the carbid receptacle and generation chamber under the generally established rule of providing a gallon of water in the generation chamber for each pound of carbid

in the carbid holder. When the generation chamber is being refilled, with the storage bell and carbid holder removed, the operator fills the chamber with water until its level coincides with or touches the bar 83.

From the foregoing it will be seen that my invention provides a simple, compact and self-contained acetylene gas generator for underground purposes, so located as to eliminate danger of the freezing of the water in either the freezing chamber or the generation chamber. When made in substantial size, the apparatus is capable of convenient operation without requiring recharging or other attention, for periods of several months at a time. The construction permits the easy removal and replacement of the storage bell and carbid receptacle for recharging or other purposes without the necessity of disconnecting and subsequently connecting up attached parts; and the stationary cylinder 7, open at both ends, is sufficiently large to permit the lowering of a workman therethrough into the generation chamber when necessary for cleaning or repairs. The indicator device affords a reliable and wholly automatic means for disclosing the condition, as to amount, of the carbid in the receptacle, and when it is necessary to recharge the latter, without the necessity of opening up the generator. By means of the agitator, the residuum or sludge in the generation chamber can be churned to a sufficiently uniform liquid condition to be readily extracted by the pump, thus dispensing with the slow and tedious method of dipping the residuum out by means of buckets. The interference device insures the proper setting of the indicator mechanism each time the carbid holder is filled; and the staples 79 and frame 80 contribute in considerable measure to the ease and facility of installing the generator and of handling the charging bell and carbid holder.

It will be manifest to those skilled in the art that detail changes might be made in the construction and relative arrangements of the coöperating parts without departing from the operative principles involved or sacrificing any of the benefits and advantages secured by the invention, and hence I do not limit the latter to the precise structure disclosed except to the extent clearly indicated in specific claim.

I claim—

In a gas generator of the character described, the combination with a tank forming at its lower end a generation chamber, of an upright stationary cylinder open at both ends within said tank having at its lower end a flange secured to the inner surface of said tank and forming with the latter an annular sealing chamber, a carbid re-

ceptacle at its lower end entering said cylinder and provided exteriorly with a series of vertical ribs resting at their lower ends upon the upper edge of the latter and also forming guides for a storage bell, a storage bell telescoping over said guide ribs and at its lower end dipping into said sealing cham-

ber, and a gas delivery pipe leading from said generation chamber.
